United States Patent Office

Des. 221,322
Patented July 27, 1971

221,322

HANDLEBAR

Carlton P. Pawsat and Robert F. Humlong, Maysville, Ky., assignors to Wald Manufacturing Company, Inc., Maysville, Ky.

Filed June 24, 1970, Ser. No. 23,645

Term of patent 14 years

Int. Cl. D12—14

U.S. Cl. D90—11

FIG. 1 is a front elevation of a handlebar showing our new design.

FIG. 2 is a side elevation view thereof as seen from the right side of FIG. 1.

The characteristic features of our design reside in the configuration and appearance of the risers of the handlebar.

We claim:

The ornamental design for a handlebar, as shown and described.
